(57) **CLAIM**

The ornamental design for an electric motorbike as shown and described.

DESCRIPTION

FIG. 1 is a front and right side perspective view of an electric motorbike;

FIG. 2 is front elevational view thereof;

FIG. 3 is rear elevational view thereof;

FIG. 4 is a right side elevational view thereof;

FIG. 5 is a left side elevational view thereof; and,

FIG. 6 is a top plan view thereof.

The broken lines illustrate portions of the electric motorbike that form no part of the claimed design.

1 Claim, 6 Drawing Sheets

FIG. 2

FIG. 3

FIG. 5

FIG. 6
